UNITED STATES PATENT OFFICE.

ARTHUR B. WARING, OF BOSTON, MASSACHUSETTS.

HEAD-COVERING AND METHOD OF MAKING THE SAME.

SPECIFICATION forming part of Letters Patent No. 296,371, dated April 8, 1884.

Application filed February 13, 1882. (No model.)

To all whom it may concern:

Be it known that I, ARTHUR B. WARING, of Boston, county of Suffolk, State of Massachusetts, have invented an Improvement in 5 Head-Coverings and Method of Making the Same, of which the following description, in connection with the accompanying drawings, is a specification.

This invention relates to improvements in 10 that class of head-covering wherein a fur nap is contained on a wool or feltable body of a material inferior to the nap, which is, as it is well known, composed of fur. In the manufacture of hats of this class the "nap," as I shall 15 designate the fur film or bat, has been produced by blowing or depositing the fur directly upon a perforated metallic cone in the usual forming-machine, and such nap is then placed over the felt cone or body—a rather expensive and tedious process; and so, also, the 20 nap has been formed by a "bowing" process and been applied to the hat in pieces. In my experiments to produce a napped hat of this 25 manner, I have discovered, by first perforating the felt hat-body produced in any usual way and placing it on the usual perforated metallic cone, that the fur for the nap may be blown directly upon the said body, and thereafter the 30 body and nap can be united or incorporated together in the manner now commonly practiced by hat-manufacturers.

My invention consists in the herein-described head-covering as an improved article of manufacture, it being composed of a perforated felt body inclosed or covered with a fur nap, and also in the method herein described of manufacturing the same.

Figure 1 represents in perspective a head-covering, shown as a hat, made in accordance with my invention, the nap being removed from one part of the body to show its perforations; and Fig. 2, a section on the dotted line xx , Fig. 1.

45 In the manufacture of head-coverings in accordance with my invention, I take a felt body, a , perforate it, as shown at b , with a sufficient number of holes of proper size to enable the passage of air through it, as the air 50 passes through the perforated metal cone of the usual forming-machine. The perforated

felt body which is to receive the nap c is blocked on a form similar in shape to the usual perforated metal cone of the forming-machine. It has also been attempted to place 55 an unperforated body of wool upon a perforated cone, and by exhausting the air from the said cone draw fine fur into the said body; but in such case the fur so deposited cannot be made to hold as closely and firmly into, and so as to 60 form a part of, the hat as in the manner hereinafter described. The felt body, having been blocked or shaped to fit the cone, is placed upon the usual perforated cone of same size in the forming-machine, and the nap is deposited 65 directly upon the perforated felt body as the nap is commonly deposited upon the usual metal perforated cone, the holes in the body permitting the finer fibers to fill therein and form, as it were, anchors for the finer covering. The 70 most desirable way of depositing the fur on the felt body is by exhausting the air from within the perforated metal cone upon which the felt body is held, such exhaustion of the air creating a draft through the perforated felt body, 75 and causing the fur being presented to it to be drawn into the perforations of and to be deposited upon the said body between the perforations therein, thus forming a bat or nap of fur that entirely covers all that part of the 80 body which has been perforated, so as to permit the passage of air through it. After a sufficient thickness of napping-fur or bat has been formed upon the felt body, the latter, with the nap upon it, is wrapped or enveloped in a damp 85 cloth and submerged in hot water, which partially sticks the nap to the perforated body, after which the nap is hardened and scalded to the body in the usual way. This very simple process results in the production of a serviceable head-covering in a most expeditious and inexpensive manner, and the fur of the nap extended more or less through the perforations of the body insures a closer and better incorporation of the nap with the felt body than as 90 heretofore practiced.

The fur-covered felt body will be blocked and finished to form a head-covering or hat in the usual manner.

In the drawings I have not shown the entire 100 fur body a as perforated; but it will be understood that the nap will be formed or deposited

only upon the perforated parts of the felt body, and so more or less of the body may be covered with a nap of fur.

The shape of the holes *b* is immaterial.

5 I claim—

1. As an improved article of manufacture, a head-covering composed of a perforated felt body having a nap deposited upon and incorporated with it, the holes in the body serving to 10 receive the accumulation of fine fibers through the body at different spots, all substantially as and for the purpose described.
2. That step in the art or method of covering

a perforated fibrous or felt body with a nap of fur which consists in depositing the said fur nap upon the body and through the perforations of the said fibrous or felt body while held upon a perforated exhausted former, substantially as described.

In testimony whereof I have signed my name 20 to this specification in the presence of two subscribing witnesses.

ARTHUR B. WARING.
